UNITED STATES PATENT OFFICE.

WILLIAM E. WHITE, OF CHICAGO, ILLINOIS.

CROSS BRACING FOR STRUCTURAL MEMBERS.

Application filed January 21, 1925. Serial No. 3,863.

To all whom it may concern:

Be it known that I, WILLIAM E. WHITE, a citizen of the United States, and resident of Chicago, in the county of Cook and State 5 of Illinois, have invented certain new and useful Improvements in a Cross Bracing for Structural Members, of which the following is a specification.

My invention relates to building construction accessories and particularly to a 10 novel device intended for use in spacing structural elements.

The use of so-called metal lumber is rapidly increasing, this product being commonly 15 in the form of light gauge pressed steel channel shaped members, two of which are placed back to back and united through their webs by welding. These so-formed elements are commonly employed in floors and of 20 necessity means must be provided for spacing the same in anticipation of the application of permanent floor and ceiling elements. Inasmuch as the spacing devices perform only a temporary function, that of spacing—or in effect limiting the spacing— 25 of the structural elements, they are commonly constructed of light weight and should be inexpensive. However, one of the principal items of cost in connection with the placing of these structural elements is that 30 of labor incident to their accurate location in proper spaced relation according to the specifications. Heretofore this has been accomplished by measuring and marking out 35 the location, then applying a strap or wire, one end of which is passed underneath and bent around the lower flange of one structural element, while the opposite end is passed under and bent over the flange of an adjacent element. In this system the accuracy 40 depends upon the workmen and furthermore considerable time is required for the proper positioning of the spacing device, particularly in view of the fact that it must be 45 placed underneath one of the structural elements.

One of the objects of my invention is to 50 provide spacing means of predetermined length by the use of which all measuring and marking is eliminated with the result 55 that the work of installation may be performed by unskilled labor with the certainty of accurate location of the beams.

A further object is the provision of a device of the character described so arranged

that an outside lower flange of a structural element is engaged, thus avoiding the necessity for passing the spacing device underneath the beam. The opposite end is preferably arranged to be distorted to engage 60 the upper inside flange. Inasmuch as the distortion is accomplished by a hammer blow, the time required is very short.

The invention will be more readily understood by reference to the accompanying 65 drawing, wherein—

Figure 1 is an end elevation of a plurality of so-called metal lumber elements showing my improved spacing devices applied thereto; 70

Figure 2 is an enlarged sectional view of one of the spacing devices as applied;

Figure 3 is a plan view thereof;

Figure 4 is a perspective view of the lower hook element which I employ; and 75

Figure 5 is a view similar to Figure 4, showing the application of the hook to a structural element having a short flange.

In the drawings, it will be seen that the improvement is applied to structural elements consisting of channel shaped pressed steel members placed back to back, and in their final form consisting of an I-beam having a web, 10, flanges 11 and marginal flanges, 12. These structural elements are 80 intended to be located in suitable spaced relation in order to support a floor. These I-beams commonly vary in height from eight to twelve inches and the marginal flanges, 12, vary in height from one-half to three-quarters of an inch. The spacing device of 85 my invention is intended to accommodate itself to variations in the flange width, a predetermined length of spacer being employed in order to secure the requisite lateral spacing of the structural elements. 90

The spacing device comprises a member, 13, which may be of strap iron or wire as desired, the former being illustrated. This member may be of light gauge and relatively 100 flexible inasmuch as a tensional strain only is exerted thereon.

Connected to the lower end of the spacing element by means of a single rivet, 14, is a hook member formed of relatively stiffer metal and consisting of a shank 15, a tongue, 16, and a pair of arms, 17, bent into a right angle and underlying the tongue 16. Looking 105 at the device from its side a triangular space is thus formed which is adapted to re- 110

ceive the marginal flange 12, of a structural element. The arms 17, fit around the angle of the flange 12, while the tongue 16 overlies the edge of the flange. A diagonally upward pull is resisted by the tongue 16. The hook is engaged with the flange by oscillating the hook member into position. The top edge of the marginal flange enters the space between the terminal points of the tongue 16 and the arms 17 and the hook is then rotated into the position shown in Figure 2.

On the opposite end of the spacing element 13, I provide a hook of somewhat different construction, this being likewise secured to the spacer by a single rivet 18. The upper hook is also constructed of relatively stiffer metal and comprises a shank 19, a tongue 20, and a pair of arms 21, formed to extend in a straight line parallel to the tongue 16. After being located in the dotted line position of Figure 2, a hammer blow on each of the arms serves to bend the same into final position, the downwardly bent portions 22, lying against the structural member. Thus it will be seen that the hooks are securely interlocked with respective marginal flanges of adjacent structural elements and the spacing thereof is positively fixed by the designer and cannot be changed by carelessness or intent on the part of the erector.

The two hook elements readily adapt themselves to variations in width of the marginal flange. This is illustrated in Figure 5 so far as the lower hook element is concerned, the shortest flange being illustrated. Of course the width of the upper flange is immaterial as the hook element will cooperate therewith under all circumstances, the only difference being in the length of the part 22, which is bent over the angle of the flange.

The construction is capable of wide variation in material and construction. Wire elements may be employed and changes in the shape of the hook elements be made, all without departure from the spirit of my invention.

I claim:

50 1. Means for bracing and for establishing a fixed spacing of metal lumber elements comprising a relatively flexible straight length of metal, means on one end of said length of metal for interlocking with a flange of said lumber by a relative rotation of the said means and said lumber, and means on the opposite end for effecting hook engagement with a flange on an adjacent metal lumber element.

60 2. Means for bracing and for establishing a fixed spacing of metal lumber elements comprising a relatively flexible straight length of metal, means at one end thereof for interlocking with a marginal flange of said lumber, and means on the opposite end

of said length of metal for interlocking with a flange on the opposite side of an adjacent lumber element.

3. Means for bracing and for limiting the lateral spacing of structural elements for floors comprising a spacing element of predetermined length, means on one end thereof for interlocking with a bottom flange of a structural element by an oscillating movement of said means, and means on the opposite end adapted to be distorted to firmly engage a top flange of an adjacent structural element.

4. Means for establishing a fixed lateral spacing of structural elements, comprising a spacing member of predetermined length, and hook elements on the respective ends of said member, one of said hook elements being adapted to interlock with a flange by oscillating said hook element, and the other hook element being adapted to be interlocked with a flange of an adjacent structural element by distortion of said hook element.

5. Means for establishing a fixed lateral spacing of structural elements, comprising a flexible spacer of predetermined length, and interlocking devices of relatively stiffer metal connected to the ends of said spacer, said interlocking devices being shaped to interlock with the flanges of adjacent structural elements.

6. Means for establishing a fixed lateral spacing of structural elements, comprising a relatively flexible spacer, and relatively stiffer metal interlocking devices secured to the respective ends of the spacer, one of said interlocking devices being of fixed form and the other of said devices being adapted to be distorted to effect interlocking engagement with a flange of a structural element.

7. Means for establishing a fixed lateral spacing of structural elements, comprising a relatively flexible spacer of predetermined length, and hooks on the respective ends of the spacer, one of said hooks being shaped to engage and interlock with a bottom flange of a structural element and the opposite hook being constructed to be distorted into hook engagement with the top flange of an adjacent structural element.

8. Means for spacing and bracing beams comprising, in combination, a flexible strip of predetermined length and adapted to function only when under tension, and means on the respective ends of the spacer for interlocking with the flanges of the beams, the interlocking means at one end being adapted to be distorted to effect final holding engagement.

9. Means of the class described comprising, in combination, adjacent flanged beams and relatively flexible straight spacers of predetermined length adapted to function only under tension, one end of the spacer having hook engagement with a flange on

the upper portion of a beam, and the other end of the spacer having hook engagement with a lower flange on the adjacent beam.

10. In means of the class described, the combination with a pair of parallel beams and spacing and bracing devices associated therewith, said devices comprising a spacer of predetermined length having a hook at one end adapted to engage with a depending

flange by a relative rotation and provided 10 on the opposite end with means adapted to engage an upstanding flange the engaging device being distorted into final holding engagement.

Signed at Chicago, Illinois, this 16th day 15 of January, 1925.

WILLIAM E. WHITE.
